SUN SUIT

Nathalie Nicoli, San Francisco, Calif.

Application May 16, 1949, Serial No. 2,696

Term of patent 14 years

(Cl. D3—17)

To all whom it may concern:

Be it known that I, Nathalie Nicoli, a citizen of the United States, residing at 375 Sutter Street, city and county of San Francisco, State of California, have invented a new, original, and ornamental Design for a Sun Suit, of which the following is a specification, reference being had to the accompanying drawing, forming part thereof.

Fig. 1 is a front elevation of a sun suit showing my new design:

Fig. 2 is a rear elevation of the sun suit shown in Fig. 1;

Fig. 3 is a side elevation; and

Fig. 4 is a top plan view thereof.

I claim:

The ornamental design for a sun suit, as shown.

NATHALIE NICOLI.
